UNITED STATES PATENT OFFICE.

ALEXANDER MARCY, OF TORONTO, CANADA, ASSIGNOR OF ELEVEN-TWENTIETHS TO JOSEPH HANAUER, OF OMAHA, NEBRASKA.

TRANSPOSING-KEYBOARD.

SPECIFICATION forming part of Letters Patent No. 517,874, dated April 10, 1894.

Application filed April 13, 1893. Serial No. 470,180. (No model.)

To all whom it may concern:

Be it known that I, ALEXANDER MARCY, a commercial traveler, a citizen of the United States, residing in Toronto, in the county of York, in the Province of Ontario, Canada, have invented new and useful Improvements in Transposing Piano-Actions and Keyboard-Instruments; and I do hereby declare that the following is a full, clear, and exact description of the same, and that the same has never been patented by myself or others in this or any other country with my knowledge or consent.

My invention consists of making piano actions, key-boards and key-board frames, for any of the various piano scales, so that when the key frame is unlocked, the key frame and keys, may be shifted for the purpose of transposing the music, so as to render the music at any pitch of tone desired, while playing the music in the scale, or key, as written.

The invention has for its object to provide simple, efficient, and inexpensive attachments to musical instruments, so that when the key frame is unlocked, the action will be separated from the keys, and allow the key frame, and keys, to shift right and left, and allow the keys to move up and down, and not come in contact with the lifts or action stems, and when the key frame is locked, in any position it may have been adjusted, all parts of the key frame, keys, and the action, will resume their proper place, and be firmly held in their normal position. I attain these objects by the mechanism illustrated in the accompanying

ings in which—

Figure 1, represents a section of a piano action illustrating the key-board frame locked, and the normal position of the parts when constructed according to my invention. Fig. 2, represents a cross section of the same, and illustrating the key frame unlocked, with the lifts clear of the keys, preparatory to shifting the key frame and keys, and Fig. 3, represents a longitudinal section on the line A—B of Fig. 1.

Similar figures refer to similar parts throughout the several views.

I provide action brackets, 1, resting on the casing, 2, back of the flange rail, 3, and stationary rail, 4, with a flat surface to receive

the flange rail, 3, and stationary rail, 4. The flange rail, 3, is jointed to the stationary rail, 4, with hinges, 5, the springs, 6, are secured to the stationary rail, 4, at each end, outside of the action, and operates on the lower edge of the flange rail, 3, and holds it in its normal position, when the key-board frame, 7, is locked Fig. 1, and when the key-board frame, 7, is unlocked Fig. 2, the springs, 6, allow the flange rail, 3, to swing forward and raise the lifts, 8, off and in front of the key blocks, 9, and allow the keys, 10, to shift right and left and move up and down, and not come in contact with the lifts or action stems, 8, while the key-board frame, 7, is unlocked.

The felt, 11, on the key blocks, 9, assures noiseless action. The retaining bar rods, 12, passing between the swings, 13, have a thread on each end, the thread on one end secures them to the flange rail, 3, the thread on the other end provides means to adjust the retaining bar, 14. When the key-board frame, 7, is locked Fig. 1, the flange rail, 3, the swings, 13, and lifts, 8, must be free from the retaining bar, 14, so they can have free action with the keys, 10. The regulating screws, 15, on the ends of the lifts, 8, have holes, 16, in them so they can be run up or down to adjust the length of the lifts, 8, the deflecting lifts, 8, which is claimed in my transposing key-board Patent No. 461,616, dated October 20, 1891, provides means to have the lifts, 8, about equally spaced from center to center at the lower end where they connect with the keys, 10.

The swinging flange rail, 3, has a lever, 17, projecting below the flanges, 18, for the jack, 19, to work against and swing the flange rail, 3. The jack, 19, is secured under the casing, 2, the long end passing up through the casing, 2, so as to work against the flange rail lever, 17. I provide a stop rod, 20, which is secured to the jack, 19, in a flexible manner and is bedded in the casing, 2, under the key-board frame, 7, and extends at least half an inch in front of the center bar of the key-board frame, 7, when in its normal position. The blade projecting up on the front end of the stop rod, 20, is an inch or more long and half an inch or more in height so as to extend half as high at least as the bar of the key-board

frame, 7. I provide twelve notches, 21, on the under side of the front edge of the center bar of the key-board frame, 7, said notches, 21, are about half the depth of the bar. The 5 notches, 21, correspond with the spacing of the lifts or action stems, 8, the stop rod, 20, with the blade on the front end is arranged so as to hold the key-board frame, 7, in any 10 position it may have been adjusted. About 10 half of the blade on the stop rod, 20, will be in front of the center bar of the key-board frame, 7, when in its normal position, and the other half of the blade will be in one of the notches, 21, in the bar and prevent the 15 key-board frame, 7, from moving. When adjusted the blade will be free from the key-board frame, 7, the bar in the key-board frame, 7, will cover half of the blade when in its normal position and the other half will 20 extend in front of the bar and should be covered with a block, 26, so as to hold the blade firmly in position. The jack, 19, the jack rod, 22, leading to a foot pedal, the springs, 6, the action brackets, 1, the flange rail lever, 25 17, and the retaining bar rods, 12, consist preferably of metal.

When the jack rod, 22, leading to a foot 30 pedal is drawn down it deflects the jack, 19, forward and moves the stop rod, 20, forward and unlocks the key-board frame, 7, swings the flange rail 3, forward, and raises the lifts or action stems, 8, off of the keys, 10, so the 35 keys, 10, and the key-board frame, 7, can be shifted right and left, and the keys, 10, moved up and down, and not come in contact with the lifts or action stems, 8, while the key-board frame, 7, is unlocked.

The stop rod, 20, is secured to the jack, 19, in a flexible manner when the jack rod, 22, 40 leading to a foot pedal is drawn down it deflects the upper end of the jack, 19, forward and slides the stop rod, 20, forward and frees it from the front edge of the center bar, 23, of the key-board frame, 7, so the key-board 45 can be shifted, when the action and key-board are in their normal position the blade projecting upon the front end of the stop rod, 20, enters one of the twelve notches in the front edge of the center bar of the key-board 50 frame and holds it firmly in its normal position.

The lever, 24, has cogs in a circling form on the back end these cogs mesh in a rack secured to the back bar, 25, of the key-board 55 frame, 7, by moving the front end of the lever 24, that is under the front edge of the piano casing, 2, the key-board and keys are moved right and left.

Having thus fully described my invention, 60 I claim as new and desire to secure by Letters Patent—

1. In piano actions, the combination of a swinging flange rail and a movable transposing key-board, for the purposes set forth.
- 65 2. In piano actions, the combination of an adjustable retaining bar beneath the swings

and a movable transposing key-board, for the purposes set forth.

3. In piano actions, the combination of a swinging flange rail jointed to a stationary rail and an adjustable retaining bar beneath the swings and secured to the swinging flange rail, and the springs secured to the stationary rail, for the purposes set forth. 70

4. In piano actions, the combination of a 75 swinging flange rail jointed to a stationary rail, an adjustable retaining bar beneath the swings and secured to the swinging flange rail, the springs secured to the stationary rail, and the flanges secured to the said swinging flange rail, for the purposes set forth.

5. In piano actions, the combination of a swinging flange rail jointed to a stationary rail, an adjustable retaining bar beneath the swings and secured to the swinging flange 85 rail, the springs secured to the stationary rail, the flanges secured to the said swinging flange rail, and the swings connecting the said flanges with the lifts or action stems, for the purposes set forth. 90

6. In piano actions, the combination of a swinging flange rail jointed to a stationary rail an adjustable retaining bar beneath the swings, and secured to the swinging flange rail, the springs secured to the stationary rail, 95 the flanges secured to the said swinging flange rail, the swings connecting the said flanges with the lifts or action stems, and the lifts or action stems with the lower ends where they connect with the keys about equally spaced 100 from center to center, for the purposes set forth.

7. In piano actions, the combination of a swinging flange rail jointed to a stationary rail, an adjustable retaining bar beneath the 105 swings and secured to the swinging flange rail, the springs secured to the stationary rail, the flanges secured to the said swinging flange rail, the swings connecting the said flanges with the lifts or action stems, the lifts or action 110 stems with the lower ends where they connect with the keys about equally spaced from center to center, and the regulating screws on the lower ends of the said lifts or action stems, for the purposes set forth. 115

8. In piano actions, the combination of a swinging flange rail jointed to a stationary rail, an adjustable retaining bar beneath the swings and secured to the swinging flange rail, the springs secured to the stationary rail, 120 the flanges secured to the said swinging flange rail, the swings connecting the said flanges with the lifts or action stems, the lifts or action stems with the lower ends where they connect with the keys about equally spaced 125 from center to center the regulating screws on the lower ends of the said lifts or action stems, and a movable transposing key-board, for the purposes set forth.

9. In piano actions, the combination of a 130 swinging flange rail jointed to a stationary rail, an adjustable retaining bar beneath the

swings and secured to the swinging flange rail, the springs secured to the stationary rail, and a jack secured to the casing, for the purposes set forth.

5 10. In piano actions, the combination of a swinging flange rail jointed to a stationary rail, an adjustable retaining bar beneath the swings and secured to the swinging flange rail, the springs secured to the stationary rail, a jack secured to the casing, and the jack rod leading to a foot pedal, for the purposes set forth.

11. In piano actions, the combination of a swinging flange rail jointed to a stationary rail, an adjustable retaining bar beneath the swings and secured to the swinging flange rail, the springs secured to the stationary rail, a jack secured to the casing, the jack rod leading to a foot pedal, and a movable transposing key-board for the purposes set forth.

12. In piano actions, the combination of a swinging flange rail jointed to a stationary rail, an adjustable retaining bar beneath the swings and secured to the swinging flange rail, the springs secured to the stationary rail, the action brackets resting on the casing back of the keys, and back of the said stationary and swinging flange rail, and a movable transposing key-board, for the purposes set forth.

13. In piano actions, the combination of a swinging flange rail, an adjustable retaining bar, the springs, the flanges, the swings, the lifts or action stems deflected as shown the

regulating screws, the jack, the jack rod, the action brackets resting on the casing back of the keys and back of the stationary and swinging flange rail, and a movable transposing key-board for the purposes set forth.

14. In pianos the combination of a swinging flange rail, an adjustable retaining bar beneath the swings, the lifts or action stems, deflected as shown so the lower ends of the lifts or action stems will be about evenly spaced from center to center, and a movable transposing key-board, for the purposes set forth.

15. In piano actions, the combination, of a stop rod with one end secured in a flexible manner to the jack and the other end having an adjustable connection with a movable transposing key-board for the purposes set forth.

16. In pianos the combination of a swinging flange rail, an adjustable retaining bar beneath the swings and secured to the swinging flange rail, the springs pressing against the said swinging flange rail, a jack secured to the casing, a stop rod with one end secured to the jack in a flexible manner and the other end having an adjustable connection with the key-board frame, and a movable transposing key-board for the purposes set forth.

ALEXANDER MARCY.
